CRAYON HOLDER AND PROTECTOR

Myrtle C. Dvorak, Cicero, Ill.

Application June 13, 1938, Serial No. 213,381

7 Claims. (Cl. 120—13)

This invention relates to a protector, gripping and holding device for crayons or pencils of various kinds, particularly pencils and crayon of the type used for marking articles in manufacturing processes and other industrial uses.

In certain manufacturing and production processes such as, for example, the pre-treatment of metal plates prior to enameling, or where any metal or other bulky material must be subjected to successive baths previous to application of enamel or other surface coatings thereon, it is customary that each individual steel or other metal part be marked with its appropriate number to identify it, either as to part number, job number, process, or the like. It is customary to use a colored crayon to apply such identification or mark to the part prior to the beginning of the initial step of a series of steps to which such part is subjected in the production line. It has been found that as the part is repeatedly handled or immersed in various baths the identifying mark is obliterated or rubbed off, with the result that the identifying mark must be repeatedly applied to the part by a number of persons who handle it successively; all this resulting in the necessity of having nearly every person handling the part to have a crayon always at hand. Great difficulty is experienced, especially by those persons who handle processes or steps involving application of liquid, semi-liquid or paint like materials, in gripping and holding crayon and in maintaining such crayon conveniently at hand for instantaneous use.

More particularly the invention consists of an elongated passaged handle-like gripping element formed of suitable material, preferably rubber or substantially yieldable texture, and embodying structural elements providing adjustability of the device for various size crayons and pencils.

It is therefore an object of my invention to provide an elongated handle-like substantially cylindrical holding and protecting device for crayons or pencils, preferably formed of yieldable resilient material and adapted to receive the main portion of the crayon or pencil and to hold another portion thereof in projected position.

A further object of my invention is the provision of a holding device for crayons or pencils or the like consisting principally of a hollow cylindrical handle-like unit having a longitudinal passage therethrough for the insertion and engagement of the main portion of a crayon or pencil, and including removable ring-like elements for fastening crayons or pencils of various diameters in said unit.

A further object of my invention is the provision of a protecting and holding device for crayons or pencils and the like which is adapted to grip and hold crayons or pencils of various diameters, and permitting the crayon or pencil to be

repeatedly projected outwardly as it is used up whereby substantially all of the crayon or pencil will be used up, and at the same time providing a convenient gripping and holding means regardless of the length of the crayon or pencil. 5

A further object is the provision of a crayon protecting and holding device for various sizes of crayons or pencils which is longitudinally passaged and has elastic elements for frictionally mounting the crayon or pencil therein, and which has one or more external flat surfaces to prevent rolling of a unit when it is laid down from time to time. 10

Other and further important objects of my invention will be apparent from the description 15 in the specification and in the accompanying drawing.

This invention (in a preferred form) is illustrated in the drawing and hereinafter more fully described. 20

On the drawing:

Fig. 1 is a side elevational view of my crayon holder and protector.

Fig. 2 is an enlarged cross sectional view 25 through the center therein.

Fig. 3 is a cross sectional view taken on line 3—3 of Fig. 1.

Reference numeral 10 designates a cylindrical or tubular body, preferably made of rubber or composition thereof with other materials to impart yieldability, resiliency and flexibility. Said hollow body 10 is preferably formed with enlarged end portions of bulb-like shape designated by 10a and 10b respectively. Numeral 11 designates a central longitudinal passageway of 30 relatively large size which is defined by an annular cylindrical wall, and the same is preferably formed in the molding of the body in a single complete unit. Passageway 11 extends throughout the length of the body as clearly shown in 40 Fig. 2, and at both the opposite ends is enlarged adjacent the ends of the body to form enlarged annular portions 12 of said passage at opposite ends respectively. Said enlarged portions are substantially the shape of an annular groove, 45 and their formation forms annular shoulders 13 at opposite ends respectively of the passage 11.

The opposite extreme ends of the body have formed integrally therewith annular flanges 14 which preferably project inwardly and into the 50 passageway, and the flanged ends of the body at said opposite ends are preferably substantially thin so that said flanges are elastic and stretchable to permit insertion and mounting of annular ring elements or ring members 15 which 55 are preferably of a size to fit snugly within the enlarged end portions 12 of the passage 11 and which preferably seat against the shoulders 13, as indicated in cross section in the upper portion of Fig. 2. 60

The flanges 14 are so formed that they project inwardly to either removably hold an annular gripping ring or member 15 or to frictionally engage and grip the external surfaces of a pencil, 5 crayon or the like.

It will be apparent that when the larger sizes of crayon or pencil are inserted in the holder, that is, those of a diameter which will substantially fill the passageway 11, the flexible flanges 10 14 will first be stretched outwardly to enlarge the diameter of the openings which either or both thereof define openings to permit insertion of a crayon, pencil or the like, whereupon the natural tendency of the rubber will grip and hold the 15 pencil in the desired position with respect to the body 10.

In many and various industrial processes, crayons, pencils and marking devices of different sizes and diameters are employed, and for this 20 reason my invention includes means providing for gripping, holding and protecting of crayons or pencils of various sizes. When pencils or crayons of the range of smaller diameters are to be mounted, any one of a number of sizes of removable rings 15, preferably made of rubber or rubber composition, may be inserted in one or both of the enlarged portions 12 of the longitudinal passageway 11, the outside diameter thereof preferably being slightly greater than the diameter of the 25 opening defined by flanges 14. In the insertion of such disks, ring elements or members, the flanges 14 are flexed or stretched outwardly on diametrically opposite sides and the ring members 14 are easily inserted into position against 30 the angular shoulders 13. The internal aperture 15a of the ring members or ring elements 15 are of a range of sizes so as to cause a snug fit for an inserted crayon or pencil, that is, so that the fit will be such that a sufficient friction results to 35 grip the crayon or pencil and hold it during normal writing operation, but which will also be such as to permit manual insertion or selective successive projection of the crayon or pencil end of the latter when it is used up in the writing process.

From reference Figs. 1 and 3, it will be noted 40 that the external surfaces of each of the bulb-shaped portions 10a is flat at opposite sides. This may aim to prevent undesirable rolling away of the crayon holder and protector when it is laid down upon any convenient supporting surface 45 during the work operations.

Various changes may be made in the embodiment 50 of the invention herein specifically described without departing from or sacrificing any of the advantages of the invention or any features thereof, and nothing herein shall be construed as limitations upon the invention, its concept or structural embodiment as to the whole or 55 any part thereof except as defined in the appended claims.

I claim:

1. A pencil holder comprising an elongated body having a central longitudinal passageway therethrough adapted to receive a crayon or the like; an annular, inwardly extending flexible flange formed integral with each end of said body; and a ring shaped element removably mounted in said longitudinal passage adjacent one of said ends, said element being adapted to frictionally engage a pencil or the like.

2. A pencil and crayon holder comprising a

flexible cylindrical body having a relatively large central longitudinal passage therethrough; integral inwardly extending flanges at the opposite ends of said body; and an annular apertured ring member removably mounted in the end of 5 said longitudinal passage, the exterior of said ring member frictionally engaging the wall of said passage and adapted to frictionally grip a pencil or the like inserted therein.

3. In a holder for crayons or pencils of varying 10 size, an elongated cylindrical body formed of a yieldable resilient material and having a central longitudinal passageway therethrough; inwardly extending flanges formed integral with said body at the end of said longitudinal passageway; and 15 a removable resilient ring insertable into said passageway and behind said flange, said ring being adapted to snugly grip the exterior surface of a pencil or the like to hold the latter in desired projected position. 20

4. In a pencil holding and protecting device, a tubular body formed of resilient material and having a relatively large central longitudinal passageway therethrough, said passageway being of greater diameter adjacent the ends of said body; an inwardly extending flange formed integral with the end of said body and extending into the enlarged portion of said passageway; and a removable pencil gripping ring frictionally and removably engaging the inner surface of 30 the enlarged portion of said passageway and adapted to hold a gripped pencil and said body in relative positions. 25

5. In a pencil holding and protecting device, an elongated tubular hollow body formed of 35 yieldable material and having a central passageway therethrough, said passageway being enlarged at its opposite ends to form annular shoulders adjacent the opposite ends respectively, and a pencil gripping ring removably mounted in one 40 of the enlarged portions of said passageway, said ring providing means whereby a pencil or the like may be held in desired position. 45

6. In a pencil holding and protecting device, a tubular body formed of resilient material and 50 of substantial circular cross section and having its opposite ends enlarged to bulb-like form, said tubular body having a longitudinal passageway therethrough terminating at the opposite ends in enlarged portions and form an annular shoulder substantially adjacent each end of said body; inwardly extending flanges formed integral with the ends of said body and overlying said enlarged hollow portions, said body and said flanges being adapted to frictionally grip and hold a pencil 55 or the like. 60

7. In a pencil holding and protecting device, a tubular body formed of resilient material and of substantial circular cross section and having its opposite ends enlarged to bulb-like form, said tubular body having a longitudinal passageway therethrough terminating at the opposite ends in enlarged portions and form an annular shoulder substantially adjacent each end of said body; inwardly extending flanges formed integral with the ends of said body and overlying said enlarged hollow portions, an elastic ring removably mounted in the enlarged hollow portion of one end of 65 said body passage, said elastic ring being adapted to frictionally grip a pencil or the like. 70
